UNITED STATES PATENT OFFICE.

JASPER BLACKBURN, OF WEBSTER GROVES, MISSOURI.

CABLE-HANGER.

1,308,979.

Specification of Letters Patent.

Patented July 8, 1919.

Application filed March 11, 1918. Serial No. 221,681.

To all whom it may concern:

Be it known that I, JASPER BLACKBURN, a citizen of the United States, and resident of Webster Groves, in the county of St. Louis and State of Missouri, have invented certain new and useful Improvements in Cable-Hangers, of which the following is a specification containing a full, clear, and exact description, reference being had to the accompanying drawings, forming a part hereof.

My invention relates to certain new and useful improvements in "cable hangers" and has for its special object the construction of a hanger made out of a continuous piece of flat spring material such as flat wire, and which hanger can be readily applied to and removed from a "messenger wire" by hand, and it also may be applied over an existing cable.

In the drawings,

Figure 1 is a perspective view of my invention.

Fig. 2 is a side view of the same when applied to a messenger wire.

Fig. 3 is a side view of the same being applied to a messenger wire.

Fig. 4 is a top plan view of the hanger applied to the messenger wire, and

Fig. 5 is a sectional view taken on a line 5—5 of Fig. 2.

Referring to the drawings, 6 indicates the body of the cable hanger which forms the cable supporting seat when the hanger is in use and 7 and 8 indicate the hanger arms which are formed integrally with the seat 6, and all being formed out of a strip of resilient material or spring wire.

The arms 7 and 8 are divergent or spread apart so that the hanger may be applied over an existing cable without spreading them apart, and also to widely separate the suspension hooks so as to give increased stability to the hanger.

The arm 8 is provided on its end with a hook 9 and the arm 7 is provided on its terminal portion with a circular or semi-cylindrical messenger seat 10, projecting from which seat is an extension 11, the extension 11 forming a supporting hook for one side of the hanger, the messenger seat 10 and the extension 11 all being formed integral with the arm 7 by first bending the arm and forming a bend or shoulder at 12, then forming the circular messenger receiv-

ing seat 10, then bending or forming the portion or extension 11 downwardly.

It will be observed that the inner edge of the extension 11 and the shoulder 12 form a tapered opening 13, in top plan view (see Fig. 4), through which in the application of or removal of the hanger from the messenger, the messenger wire passes, and in order to apply the hanger it is held in position as illustrated in Fig. 3, first passing the extended portion 11 over the messenger and then changing the position of the hanger so that the extension occupies a position along the side of the messenger and causing the seat 10 to come in contact with the bottom and sides of the messenger wire, and then by an upward pressure on the body of the hanger the hook 9 is brought to engage with the messenger.

When the hanger has been applied the resiliency of the hanger or more specifically speaking the reaction of the resiliency will cause the seat 10 and the extension 11 to firmly grip the messenger wire and prevent it from creeping.

The special improvements of this invention reside in constructing a hanger out of a flat piece of resilient spring material such as spring wire and providing one arm of the hanger with a circular messenger receiving seat to partially embrace the messenger wire and providing the seat with an extension, the inner edge of the extension forming with an opposing edge or shoulder of the seat a tapered passage-way or throat through which the messenger passes when the hanger is applied to or removed from a messenger wire.

It will further be observed that the inner edge of the extension 11 projects diagonally across the axis of the messenger.

In the form shown the inner edge of the extension 11 is formed by cutting off one corner of a strip of material.

It will further be observed that the axis of the semi-circular seat 10 when the hanger is not in use is inclined outwardly and downwardly.

The semi-circular seat 10 is of considerably greater width than the thickness of the material, and if extended would form substantially a true cylindrical body the axis of which as previously pointed out, when the hanger is not in use, projects outwardly in an inclined position, and when the hanger

has been applied the axis of the messenger seat practically coincides with the longitudinal axis of the messenger. This is made possible by the resilient or yielding action of
5 the messenger seat.

Having fully described my invention, what
I claim is:

1. A cable hanger formed from a single strip of spring material provided with a cable supporting seat having arms spread apart and bowed in opposite directions, one of said arms being provided with a circular messenger wire seat partially embracing the messenger wire and with a tapered throat
15 or opening leading to said seat and with an extension beyond the messenger receiving seat, said extension being downwardly extended to embrace the top and side of the messenger wire, and the other of said arms
20 being provided with a hook bent in a direction opposite to the messenger receiving seat formed on the first mentioned arm and adapted to engage the messenger wire on its top surface.
2. A cable hanger formed from a flat strip
25

of spring material provided with a cable supporting seat having arms spread apart laterally and bowed in opposite directions so as to give stability to the hanger and permit the same to be applied to a cable already hung, one of said arms being provided with a semicylindrical messenger wire seat, the longitudinal axis of the cylinder of which said seat is a part being inclined when the hanger is not in use downwardly and outwardly, and with an extension beyond said messenger receiving seat, the inner edge of which forms with the opposing side of the seat a tapered opening or throat, and the other of said arms being provided with a hook bent in the same direction as said extension adapted to engage the messenger wire on its top surface.

In testimony whereof, I have signed my name to this specification, in presence of the two subscribing witnesses,

JASPER BLACKBURN.

Witnesses:

S. PEEIFFER,
EDWARD E. LONGAN.
